UNITED STATES PATENT OFFICE.

HERMAN F. STUBENRAUCH, OF CHICAGO, ILLINOIS.

FOUNTAIN BRUSH OR DAUBER.

1,007,816.

Specification of Letters Patent.

Patented Nov. 7, 1911.

Application filed November 26, 1909. Serial No. 529,953.

To all whom it may concern:

Be it known that I, HERMAN F. STUBENRAUCH, a citizen of the United States, and resident of Chicago, county of Cook, and State of Illinois, have invented certain new and useful Improvements in Fountain Brushes or Daubers, of which the following is a specification, and which are illustrated in the accompanying drawings, forming a part thereof.

The invention relates to brushes and daubers used for spreading liquids or pastes, and more particularly to such devices in which provision is made for supplying the material to be spread through the back of the brush or dauber.

The object of the invention is to provide a brush or dauber of improved construction, whereby the material to be spread may be continuously supplied, as from collapsible tubes, like those now in common use for containing paints and pastes of various kinds, such as shoe and stove polish, shaving soap, and inks for stenciling.

The invention is exemplified in the structure to be hereinafter described and illustrated in the drawings, in which—

Figure 1 shows in side elevation a device embodying the features of improvement provided by the invention, the brush being covered by a protective cap; Fig. 2 is similar to Fig. 1, but shows the brush and protective cap in central section; Fig. 3 is a perspective view showing a detail of the construction; and, Fig. 4 illustrates a dauber which may be employed in the device in place of the brush illustrated in Fig. 2.

The brush is illustrated in the drawings as having a back 10, and a body 11, preferably consisting of tufts of bristles carried by the back 10 and projecting therefrom. The back 10 of the brush is apertured, as shown at 12 (Fig. 2), and a tube 13 for the delivery of material to be spread by the brush extends through the aperture 12 of the back 10 and into the body 11 of the brush, preferably to within a short distance of the face of the brush. Most desirably the tube 13 is of flexible material, such as rubber, and it is formed with a flange 14 adapted to be seated upon the back of the brush about the aperture 12.

Provision is made for supplying the material to be spread by the brush to the tube 13 under pressure. As shown, a threaded

socket 15 adapted to receive the threaded nipple 16 of a collapsible tube 17, is mounted upon the back of the brush. The threaded socket 15 is preferably supported in line with the bore of the tube 13, and immediately in rear of the flange 14, in order that the nipple 16 on entering the socket, may bear upon the flange 14, and the latter thereby constitute the gasket for confining the material delivered to the tube 13 from the nipple 16. As shown, the socket 15 is formed upon the end wall of a collar 18, which is preferably made of sheet metal and has screw threads 19 formed upon its side walls for receiving the back 10 of the brush, the latter, as shown, having complementary-formed screw threads 20 upon its periphery.

A protective cap 21 is provided for covering the body 11 of the brush when not in use. As shown, the side walls of this cap are provided with screw threads 22 for engaging the screw threads 19 formed upon the side wall of the collar 18 upon the outside. The end wall of the cap 21 preferably carries a plug 23 for entering the end of the tube 13 when the cap is applied to the brush. As shown, the plug 23 is formed by indenting the end wall of the cap.

If desired, a dauber of the form shown in Fig. 4 of the drawings may be used in lieu of the brush 10, 11, illustrated in Fig. 2. This dauber preferably comprises a back member 24 identical in construction with the back 10 of the brush, and a body 25 constructed of felt in the manner usually employed for the construction of daubers, except that it is provided with a central aperture 26 in line with the aperture of the back 24, for receiving the tube 13.

When the device is in use the collapsible tube 17 serves as a handle for manipulating the brush 10, 11, or the dauber 24, 25. When the contents of the tube 17 have been exhausted, it may be removed from the brush by merely unscrewing its threaded nipple 16 from the socket 15, and a fresh tube of material substituted for it.

I claim as my invention:—

In combination a collapsible tube having an inclined breast terminating in a screw-threaded nipple, a separable dauber-holder having an inclined surface terminating in an internally screw-threaded tubular portion adapted to engage said nipple, said tubular portion being parallel with the side walls of

said dauber-holder, the outer part of said holder being screw-threaded internally and externally and a dauber-head adapted to screw into said holder, said head having a central opening therein, a flexible tube having an annular flange on one end thereof adapted to project through said opening

and an annular flange on the free end of said tubular portion adapted to press upon said flange on said flexible tube.

HERMAN F. STUBENRAUCH.
